UNITED STATES PATENT OFFICE.

OSCAR L. RAYMOND, OF MARINETTE, WISCONSIN.

LOG-HOIST AND CAR-LOADER.

No. 822,152.

Specification of Letters Patent.

Patented May 29, 1906.

Application filed November 7, 1905. Serial No. 286,278.

To all whom it may concern:

Be it known that I, OSCAR L. RAYMOND, a citizen of the United States, residing at Marinette, in the county of Marinette and State 5 of Wisconsin, have invented a new and useful Log-Hoist and Car-Loader, of which the following is a specification.

My invention relates to certain new and useful improvements in log-hoists and car-10 loaders, and especially over my log-loader shown and described in United States Letters Patent No. 768,402, and has for its object to provide a much simpler log-loader and one that can be swung around without mov-15 ing the sled.

Another object of my invention is to provide a log-loader that can be adjusted so that the boom can swing with the log automatically.

20 A further object of the invention is to provide a derrick mounted upon a platform pivotally mounted on a sled, so that it can be quickly and easily adjusted.

With these various objects in view the invention consists of the novel features of construction, combination, and arrangements of parts hereinafter fully described, and pointed out in the claims.

30 In the drawings forming a part of this specification, Figure 1 is a perspective view of my improved derrick and log-loader in operation. Fig. 2 is a side elevation of the same. Fig. 3 is a detail view of the cap. Fig. 4 is a detail view of the pulley in the mast. Fig. 5 is a detail view of the boom, and Fig. 6 is a plan view of the cap.

Referring to the drawings, A indicates the sled, which consists of the runners A', which are connected together at their ends by cross-bars A² or by a tube having a chain passing through it, the ends being connected to the runners, to which are also connected the ends of the draft-chains A³. The runners are provided with notches A⁴, in which is mounted a central bar A⁵, the ends A⁶ being formed oval 45 in shape, and are secured in the notches by a metal strip A⁷ and a bolt A⁸, which allows the bar to rock in the notches for the purpose hereinafter described.

50 Pivotaly mounted on the bar A⁵ is a frame B, consisting of the three parallel bars B', connected together at their ends by the cross-bars B² and at the center by the bars B³. The frame is secured to the sled by a king-bolt B⁸ passing down through the central parallel bar B⁴ and bar A⁵ of the sled. Mounted on the central

parallel bar B⁴ adjacent one end is a mast C, having a reduced upper portion forming a shoulder C'. The mast is securely steadied by the braces C² and C³, connected to the 60 frame. The upper end of the mast is reduced, forming a shoulder upon which the cap D rests, carrying rings D', to which the guy-ropes E, carrying turnbuckles, are connected, the other end of the rope being connected to eyebolts carried by the frame. Extending out from each side of the cap are perforated lugs D², provided with rings to which are connected guy-ropes D³, carrying hooks at their ends adapted to be connected to 65 near-by trees for the purpose of steadyng the loader. The lower portion of the mast is slotted and is provided with a pulley F, journaled therein.

A boom G, provided with arms G', is 70 mounted on the shoulder C' of the mast C and connected to the mast by a chain H, provided with a hook at each end, connected to an eyebolt carried by the boom and mast. The outer end of the boom is provided with a 75 sleeve G², provided with perforated lugs G³, the upper lug being connected by a cable to a hook G⁴, pivoted on the bolt D⁴ of the cap. The lower lug supports the block I, to which one end of the cable J is connected, which 80 supports the block J', carrying the crotch-chains and hook J², the other end of the cable passing over the block I and through the pulley G⁵, carried by the boom G, and down and out over the pulley F and connected to the 85 ordinary double-tree L. A rope is connected to the crotch-chain, so that the boom can be drawn back after a log has been placed in position. From the foregoing description it will be seen that I have greatly improved the 90 construction of the loader, as the frame carrying the derrick can be turned to any position desired and at the same time it can be rocked in the bar A⁵, so as to throw the mast at an angle, so that the boom will swing back 95 with a log to the place desired.

The frame is locked into the position desired by chuck-blocks N, as clearly shown.

Having thus fully described my invention, what I claim as new, and desire to secure by 100 Letters Patent, is—

1. In a device of the kind described, the combination with a sled having a bar loosely mounted thereon, of a platform pivoted to said bar, and means for adjusting said platform, for the purpose described.
2. In a device of the kind described, the

combination with a pair of sled-runners loosely connected together, of a bar loosely mounted on said runners, a platform pivoted on said bar, carrying a derrick and means for adjusting said platform for the purpose described.

3. In a device of the kind described, the combination with a pair of sled-runners provided with notches, of an oval bar working in said notches, a platform pivoted to said bar, provided with a mast provided with a boom, carrying block and tackle, and means for adjusting said platform, on said sled, for the purpose described.

15 4. In a device of the kind described, the combination with a sled, of a rocker-bar mounted on said sled, a frame pivoted on said bar, a mast secured on said platform, a cap secured on said mast, a boom carrying

block and tackle mounted on said mast, and 20 means for adjusting said platform, for the purpose described.

5. In a device of the kind described, the combination of a pair of runners, loosely connected together at each end, notches formed 25 in said runners, a bar provided with oval ends adapted to rock in said notches, means for securing said bar in the notches, a platform pivoted to said bar provided with a derrick, and means for adjusting the platform in an 30 inclined position to the runners, for the purpose described.

OSCAR L. RAYMOND.
